(57) **CLAIM**

We claim the ornamental design for a shelled egg staging device, as shown and described.

DESCRIPTION

FIG. 1 is a front perspective view of a shelled egg staging device depicting the new design;

FIG. 2 is a top plan view thereof;

FIG. 3 is a bottom plan view thereof;

FIG. 4 is a left side elevation view thereof, the right side being a mirror image;

FIG. 5 is a front elevation view thereof;

FIG. 6 is a rear elevation view thereof;

FIG. 7 is a front perspective view of another embodiment of the shelled egg staging device depicting the new design;

FIG. 8 is a top plan view thereof;

FIG. 9 is a bottom plan view thereof;

FIG. 10 is a left side elevation view thereof, the right side being a mirror image;

FIG. 11 is a front elevation view thereof; and,

FIG. 12 is a rear elevation view thereof.
